UNITED STATES PATENT OFFICE.

ALBERT E. GATCHELL, OF NEWPORT, KENTUCKY.

CRANK FOR MACHINERY.

SPECIFICATION forming part of Letters Patent No. 257,691, dated May 9, 1882.

Application filed February 4, 1882. (No. model.)

To all whom it may concern:

Be it known that I, ALBERT E. GATCHELL, a citizen of the United States, residing at Newport, in the county of Campbell and State of Kentucky, have invented certain new and useful Improvements in Cranks for Machinery, &c., of which the following is a specification.

The object of my invention is to furnish a cheap, strong, and durable wrought-metal crank for all kinds of machinery requiring but a moderate transmission of power. This result is accomplished by cutting the entire crank from a suitable blank and piercing the head or boss of the same with an opening or enlarged eye for the reception of the shaft, said opening being formed with one or more tongues or lugs, which are subsequently bent at right angles to the web or arm, and finally fastened to the shaft either by means of screws, pins, or other suitable retaining devices. Furthermore, the smaller end of the crank has an eye or perforation to receive a wrist-pin or handle-shank of any convenient length.

My invention further consists in swaging a bead in the web or arm of the crank, so as to increase its stiffness and prevent lateral springing of the same, as hereinafter more fully described.

In the annexed drawings, Figure 1 is a front elevation of the more simple form of my wrought-metal crank. Fig. 2 is a similar elevation of a more complex form of the same. Fig. 3 is a vertical section of the latter construction, the attaching-lugs being bent at the proper angle. Figs. 4 and 5 represent modifications of the invention.

To construct the more simple form of my invention, I first take a wrought-metal blank of any suitable size and weight, and at a single operation I cut and punch therefrom the crank seen in Fig. 1. This crank has an arm or web, *a*, with a head or boss, *B*, at one end and an enlargement, *C*, at the other end, said enlargement being provided with an eye or perforation, *D*, to receive either a wrist-pin or the handle-shank, *E*. (Seen in Fig. 5.) The boss *B* has an opening, *F*, to admit the end of the shaft to which the crank is to be applied. This opening may be square or of any other shape corresponding to the end of the shaft, but in the present case it is a complete circle, except where

interrupted by a tongue or lug, *G*, having a perforation, *g*, near its free end. Furthermore, the web of this crank may be slotted at *H* for the purpose of economizing material and rendering the device as light as possible. The above-described crank having been cut from the blank at a single operation, or, at most, by successive cutting and punching operations, the lug *G* is then bent horizontally rearward or at right angles to the face of the web *A*, as seen in Fig. 3, and the device is at once ready for attachment to the shaft.

In the stiffer and more complex form of crank (seen in Fig. 2,) the opening *F* is provided with two opposing lugs, *G* *g*, *G'* *g'*, which are finally bent so as to be parallel with each other, as represented in Fig. 3, thus indicating that one, two, or more of these lugs may be employed, according to circumstances. Additional stiffness is imparted to the web of this crank by swaging therein a suitable bead or crease, *I*, of any desired shape and so arranged as to project either from the front or rear of said web, but preferably from the latter.

To apply the crank it is necessary only to insert the end of the shaft in the opening *F* of boss *B* and then pass a screw or nail through the perforation *g* of the horizontal lug *G* into said shaft; but in case both lugs are used screws are inserted in the perforations *g* *g'*; or a pin may be passed through said perforations and also through a hole in the shaft and headed up at both ends, if desired; or either one of these perforations may be tapped to receive a single long screw adapted to pass through both of the lugs *G* *G'*; but whichever construction may be employed, it is evident the pin, screws, or equivalent retaining devices fasten the crank to the shaft in the most secure manner. Furthermore, as the crank is made of wrought metal, it is evident it combines the maximum of strength with a minimum of material, thereby rendering the device applicable to all kinds of machines, implements, tools, &c., capable of being operated with a moderate amount of power. When the crank is to be applied to a wooden shaft the lugs may be indented, as shown at *g''* in Fig. 4, which indentations will be sufficient to maintain said crank in its proper position.

The boss *C* may be composed of two thick-

nesses of the blank, doubled or bent back on itself, so as to afford a more extended bearing for the handle-shank E. (Seen in Fig. 5.) Finally, in another modification, the ends of the tongues 5 G G' may be sharpened, so as to be driven into the shaft; or they may be arranged to occupy grooves in the same, a collar or band being driven or shrunk into the shaft for the purpose of affording additional security.

10 I claim as my invention—

1. A wrought-metal crank having an opening, F, to receive the shaft and one or more lugs, G G', capable of being bent so as to afford a means of attachment to said shaft, substantially as described. 15

2. A wrought-metal crank having an opening, F, to receive the shaft and one or more perforated lugs, G g, G' g', capable of being bent so as to afford a means of attachment to said 20 shaft, substantially as described.

3. A wrought-metal crank having an opening, F, to receive the shaft and one or more perforated lugs, G g, G' g', bent about at right angles to the face of said crank, for the purpose specified. 25

4. A wrought-metal crank having an opening, F, to receive the shaft, one or more lugs, G G', for attachment to said shaft, and an eye, D, to receive the wrist-pin or handle-shank, substantially as described. 30

5. A wrought-metal crank having an opening, F, to receive the shaft, one or more attaching-lugs, G G', an eye, D, to receive the wrist-pin or handle-spindle, and a stiffening bead or groove, I, disposed longitudinally of the web 35 of the crank, for the purpose specified.

6. A wrought-metal crank bent back on itself to afford a double thickness of material to receive the wrist-pin or handle-spindle, substantially as described. 40

7. A wrought-metal crank having a groove or bead swaged longitudinally of the web of the same, as and for the purpose specified.

In testimony whereof I affix my signature in presence of two witnesses.

ALBERT E. GATCHELL.
